Primary Examiner — Karen S Acker*Assistant Examiner* — Steven B Reinholdt, Jr.(74) *Attorney, Agent, or Firm* — Workman Nydegger(57) **CLAIM**

The ornamental design for a hydroponic pot, as shown and described.

DESCRIPTION

FIG. 1 is a front perspective view of a hydroponic pot;
FIG. 2 is a front elevation view thereof;
FIG. 3 is a back perspective view thereof;
FIG. 4 is a left elevation view thereof;
FIG. 5 is a right elevation view thereof;
FIG. 6 is a top plan view thereof;
FIG. 7 is a bottom plan view thereof;
FIG. 8 is a front perspective view of the hydroponic pot of FIG. 1 shown with unclaimed environment; and,
FIG. 9 is a top plan view thereof.

The broken lines in the figures depict portions of the hydroponic pot that form no part of the claimed design. The broken lines in the top portion of FIGS. 8 and 9 depict environmental subject matter that forms no part of the claimed design. The dot dash dot broken lines in the figures depict boundaries of the claim and form no part thereof.

1 Claim, 9 Drawing Sheets(56)
